UNITED STATES PATENT OFFICE.

HERBERT W. BEATTIE, OF QUINCY, MASSACHUSETTS, ASSIGNOR TO THE
SILL STOVE WORKS, OF ROCHESTER, NEW YORK.

DESIGN FOR AN UPPER SHELF-SECTION FOR STOVES OR RANGES.

SPECIFICATION forming part of Design No. 31,693, dated October 17, 1899.

Application filed September 22, 1899. Serial No. 731,358. Term of patent 14 years.

To all whom it may concern:

Be it known that I, HERBERT W. BEATTIE, a citizen of the United States, residing at Quincy, in the county of Norfolk and State of 5 Massachusetts, have invented and produced a new and original Design for Shelves for Stoves or Ranges, of which the following is a specification, reference being had to the accompanying drawing.

10 The leading feature of my design consists in the shape and ornamentation of the upper or high shelf-section adapted to be applied to a stove or range.

15 The lower portion of the design below the shelf A has the rounded-out central portion B, provided with the conventional scroll and leaf ornamentation b, extending upon opposite sides of the center line, and the scroll ornamentation C, arranged at the top and sides 20 of the portion B and extending to the wings

D, which latter are substantially ogee in outline upon their edges. The side wings are provided with the scroll and leaf ornamentation E upon their lower portions and the ornamentation F upon the upper part.

25 The portion of the back plate above the shelf A has the reversed-curve outline extending across the top, with the smooth rounded portion forming the edge G, and is provided with the scroll and leaf ornamentation 30 H, inclosing the panel h, and is provided upon its ends with the decoration J.

I claim—

35 The design for an upper shelf-section of a stove or range substantially as herein shown and described.

HERBERT W. BEATTIE. [L. S.]
